UNITED STATES PATENT OFFICE.

WILLIAM STUEBING, JR., OF CINCINNATI, OHIO, ASSIGNOR TO THE STUEBING TRUCK COMPANY, OF CINCINNATI, OHIO, A CORPORATION OF OHIO.

LIFTING-TRUCK.

1,279,481.

Specification of Letters Patent. Patented Sept. 17, 1918.

Application filed April 12, 1916. Serial No. 90,756.

To all whom it may concern:

Be it known that I, WILLIAM STUEBING, Jr., a citizen of the United States, residing at the city of Cincinnati, in the county of Hamilton and State of Ohio, have invented 5 certain new and useful Improvements in Lifting-Trucks, of which the following is a specification.

My invention relates to check mechanism 10 used in connection with lifting trucks, which check and govern the downward movement of the lifting platform of such lifting trucks, keeping the same from falling suddenly or with a thud; and it relates more particularly 15 to means connected with said check mechanism so that the elevating platform can be pulled down into normal position when it is empty and unloaded.

The lifting platform, when raised, is usually locked in position, so that the load can 20 be moved to any point, and when it is desired to lower the loaded lifting platform, the locking parts are released, and the fluid check will allow the load to gradually fall 25 with the elevating platform, to normal position.

When the lifting platform is not loaded or empty and is in an elevated position, and it is desired to lower the same, it is first 30 unlocked from its elevated position and the operator presses on said lifting platform with his foot or stands thereon in order to start it on its downward course; I overcome this by a spring I use in connection with 35 my check mechanism which is placed at a tension when the lifting platform is elevated and when released the tension of the spring pulls down said platform.

In the accompanying drawing, forming 40 part of this specification.

Figure 1, is a plan view of the lifting truck,

Fig. 2, is a side view, the elevating platform being raised,

Fig. 3, is a similar view with the elevating platform partly lowered,

Fig. 4, is a longitudinal section of the check mechanism, part being in full lines, and

Fig. 5, is a cross-section on line 5—5 of Fig. 4.

The truck is formed of a lower frame consisting of a front head 1, two rearwardly extending connecting bars 2 connected to

the back axle 3 and connected in the front 55 with the head 1 through the pins 4 and 5. This lifting or elevating platform of the truck consists of two links 6, fulcrumed on the shaft 3 and carrying at their other bearing ends the shaft 7, see Fig. 1. To the shaft 60 7 I connect on both sides the link bars 8, extending forward to the front of the truck and connected through the pins 9 to the links 10. The links 10 in turn are connected 65 through pins 4 to the front head.

In the front head 1, I carry the bearing 12 and through this bearing I operate the fork 13 carrying at its bottom end the bearings 15—15, and through these bearings I place a shaft 16 and on said shaft I place 70 the two front wheels 17 on the outside of the fork 13, the shaft 16 making a bearing for the said wheels. On the shaft 3 I place the rear wheels 18, thus constructing a four 75 wheeled device.

The fork 13 with its bearing 19 operating in bearing 12 will allow the two front wheels 17 to swivel as in the manner of wagons.

The fork 13 is constructed with a flange 80 40, which flange acts as a thrust bearing against the face of the bearing 12 on head 1 thus supporting, through the agency of the wheels 17 and fork 13, the head 1.

At the other end of fork 13, I carry the 85 two bearings 20—20, through these bearings I place the shaft 21 in such a position as to lock the fork 13 between the upper and lower face of bearing 12 in the head 1. Pivotally connected on shaft 21 and operating 90 between the bearings 20—20 of fork 13, I connect the handle, lever or tongue 22.

At the lower end of the handle 22 I provide the bearing point 23, to which I connect the hook 24 through pin 25. Extending 95 away from bearing 23 is a short arm 26. Between the tongue 22 and the hook 24, I connect a spring 27. The short arm 26 acts as a stop for hook 24 limiting its travel, when the spring 27 operates to pull said 100 hook back into its normal position, which operation will be hereinafter described.

On the top of the head 1, I place the bearing 28 carrying a pin 29, which pin supports the pawl 30, and extending forward on the 105 pawl, I provide the treadle 31; the two bearing made integral and operate on the pin 29 as a pivotal point.

To the pawl 30 I connect the spring 32 which at its other end is fastened to front head 1 at point 33.

On the elevating platform I connect the bridge 34 extending across the platform and connecting at each side with link bars 8—8, and on the bridge, at its front I place an engaging hook 35 for the hook 24 and another engaging hook 36 for the pawl 30.

10 At the rear the bridge 34 is provided with a raised abutment 37 which limits the forward movement of the platform upon which the articles to be lifted are placed; these platforms are usually made of wood and are 15 raised so that the truck can be placed under them when down in order to elevate the same.

To operate the truck when the elevating platform is in its lowest position, the operator 20 forces the hook 24 down into engagement with the hook 35 on bridge 34, as shown in Fig. 2, the handle 22 is then pulled into a horizontal position forcing the link bars 8 which are connected to the bridge 34, to elevate 25 on the links 10 and allow the pawl 30 to engage with the hook 36 on bridge 34, thus locking the elevated platform with its load, and to disengage the hook 24 the operator again raises handle 22 and this forces the 30 hook 24 rearwardly, until it passes out of contact with the hook 35, and then, through the spring 27 the hook 24 is quickly and automatically pulled up into normal position against stop 26, see Fig. 5; the spring 27 35 having been placed at tension when the hook 24 was first placed into engagement with the hook 35.

After the platform is raised and locked into position and the hook 24 has automatically been released from hook 35, the tongue or lever 22 is then free to turn in a complete circle laterally, thus allowing the fork 13 which carries the two front wheels 17 to turn in all directions. When the elevating platform 40 is down the handle and front wheels can also be moved laterally and in a circle the same as when the platform is elevated; thus it will be seen that the handle and 45 wheels are free to turn in all directions when 50 the platform is down or up.

In order to lower the elevating platform after it has been elevated, the operator steps on treadle part 31 of pawl 30, thus disconnecting pawl 30 from hook 36, allowing the 55 platform to descend.

I will now describe my fluid check and its operation. In order to carry out my invention, I attach, to the cross-bar 38, on the lower frame part 2, two diverging bars 50—50, 60 which at their forward ends are attached to the side links 2—2. To said cross bar 38, I attach a fork 51 and in this fork I fulcrum the rear end 52 of the check, through medium of pin 53. To the rear end 52 of the 65 check I attach the cylinder 54 of said check

and into this cylinder passes the piston rod 55. On the piston rod, at its rear, I attach a piston or piston head 56. The piston carries a washer or piston ring 57 to keep it tight against the inside wall of the cylinder. 70

At one end of the piston I place a valve 58, held against the piston by spring 59, which spring is held in place by a washer 60 held by pin 61. Through the piston I place the passage ways or elongated slots 62, in the present instance using three. Through the valve 58, I place a by-pass 63, through which oil can pass into an annular recess 64 in the piston into the space 71 in cylinder in front of the piston, when the loaded or unloaded 80 elevating platform is lowered.

At its forward end the cylinder 54 is closed by a cap or head 65, into which is placed a stuffing box 66, and a stuffer 67. The piston rod 55 is pivotally attached to a forked part 85 68, which in turn is connected to short arm 69, made integral with the bridge 34 of the lifting or elevating platform.

Around the piston rod 55 and between the piston 56 and the part or head 65, I place a 90 coiled spring 70.

It will readily be apparent that when the elevating or lifting platform, with the load, is elevated, as above set forth in the operation of the truck itself, the upward and forward movement, by reason of piston rod 55 being connected as described to bridge 34 on the elevating platform, will follow the operation of said lifting platform and move upward and forward therewith; thus pulling out said piston rod 55 and piston 56 and connections, and thus place a tension on the spring 70, the oil in space 71, during this operation being forced through the elongated slots 62 in the piston 56 into the space 72 105 back of the piston; the force lifting valve 58 off its seat and when the lifting operation is complete, the spring 59 forces valve 58 again against the piston 56 and as long as the platform remains elevated, the parts 110 will remain in this position, but as soon as the elevating platform is released, the oil in the space 72 in rear of the piston which has passed there during the lifting operation, will slowly run or seep through by-pass 63 115 into the annular recess 64 in the piston, into space 71 forward of the piston 56, this operation continues until the oil has passed into said space 71 forward of the piston 56, by this time the lifting platform is down in 120 position again.

This fluid check will operate perfectly when a load is on the lifting or elevating platform and the locking means are released, and various forms of fluid checks have been 125 used for this purpose, but when the platform is in an elevated position and locked, without a load, it has been necessary when the locking mechanism has been released to give the elevating platform an initial down- 130

ward movement by some manual means, as for instance, by standing on the platform or pushing downward upon it; but with my spring which is placed at a tension when the 5 elevating platform has been pulled up or lifted, will by itself pull down the lifting platform without the interposition of manual means, and this is one of the features of my invention.

10 It will be understood that this check and a tension device may be used by me in connection with any form of lifting truck and it will also be evident that the same is capable of some modification, and I do not wish 15 to limit myself to the precise construction herein shown and described.

What I claim as new and my invention and desire to secure by Letters Patent, is:

1. In a lifting truck, a frame, a platform 20 elevatable with respect to said frame, means to hold said platform in elevated position, a fluid check device connected to said frame and platform, and a spring carried by said check device, said spring being arranged to 25 be stressed by said check device when the platform is elevated whereby upon the release of said platform from its holding means an initial downward impetus is given said platform by said spring.

30 2. In a lifting truck, a frame, a platform elevatable with respect to said frame, means to hold said platform in elevated position, a fluid check device connected to said frame, and platform, a spring carried by said check 35 device, said spring being arranged to be

stressed by said check device when the platform is elevated whereby upon the release of said platform from its holding means an initial downward impetus is given said platform by said spring placed on 40 the inside of said fluid check device and operating therein.

3. In a lifting truck, a frame, a platform elevatable with respect to said frame, means to hold said platform in elevated position, a 45 fluid check device connected to said frame and platform, a spring, said spring operating in connection with said fluid check and arranged to be placed under strain when the platform is elevated, whereby upon the release of said platform from its holding means an initial downward impetus is given 50 said platform by said spring.

4. In a lifting truck, a frame, a platform elevatable with respect to said frame, means 55 to hold said platform in elevated position, a fluid check device connected to said frame and platform, a spring, said spring arranged to be placed under strain when the platform is elevated, whereby upon the release of said platform from its holding means an initial downward impetus is given 60 said platform by said spring.

Signed at Cincinnati, Hamilton county, Ohio, this 25th day of January, 1916.
